UNITED STATES PATENT OFFICE.

WILLIAM F. SCHMIDT, OF WYANDOTTE, MICHIGAN, ASSIGNOR TO ALL METAL PRODUCTS COMPANY, OF WYANDOTTE, MICHIGAN, A CORPORATION OF MICHIGAN.

TOY PISTOL.

Application filed December 18, 1926. Serial No. 155,650.

My invention relates to toy pistols, and objects of my improvements are to provide a toy pistol in which there shall be no danger of injury to the hand of the operator, that can only be fired when the parts are in proper operative position and that shall secure cheapness of construction and facility in assembling.

I secure these objects in the apparatus illustrated in the accompanying drawings, in which:

Figure 1 is a side elevation of a pistol embodying my invention.

Figure 2 is a longitudinal central section, the parts being shown in the "discharged" position.

Figure 3 is a similar view to Figure 2, the stock, or handle, being turned to the position to set the parts in "firing" position.

Figure 4 is a view similar to Figure 3, the handle being returned to its normal position and the parts being in "firing" position.

Figure 5 is a section on the line V, V, Figure 4.

Figure 6 is a section on the line VI, VI, Figure 4.

Figure 7 is a perspective view of the detached handle, or stock.

Figure 7^a is an edge elevation looking in the direction of the arrow, VII^a, Figure 7.

Figure 8 is a detail section on the line VIII, VIII, Figure 4.

Figure 9 is a detail section on the line IX, IX, Figure 1.

Figure 10 is a view similar to Figure 9 showing a modified construction.

a is the stock, or handle, and b is the barrel. b² is an enlarged portion of the barrel forming a guide for the cork c. b³ is a slot in the lower portion of the barrel toward the rear end thereof, b⁴ indicates a shoulder formed by slightly cutting away the lower portion end of the barrel to a considerable less width than the diameter to present a catch to be engaged by the retracting wire. b⁵ is an upward extension of the barrel b to permit of a free upward motion of the retracting wire. This may or may not be used. b⁶ and b⁷ are similar parallel flanges turned down from the edges of the slot b³ at the rear portion of the barrel b.

d is a piston reciprocating in the barrel b

and adapted to be projected forward by the spring s. e is a retracting rod, the forward end of which is rigidly attached to the piston d coaxial therewith, which extends rearwardly through the spring s, bends downward through the slot b³ forming the loop e² then upward into the barrel b then backward and bending downward to form the engaging catch e³.

f is a wire engaging the loop e² at its rear end, extending forward and bending upward forming the loop f³ in the guide b² of the barrel b.

The handle is made of sheet metal and of uniform approximate rectangular cross-section, except at the upper left hand portion where it is split on each side from about the center of its upper edges downward, and parallel to the edges of the handle. The metal in front of each of said splits is bent sharply inward at a², a³ and a⁴ and then again outward forming parallel flanges a³ and a⁴ which are also parallel to the side surfaces of the handle leaving the slots k, k, between the inner edges of the bent in portions and the adjacent edges of the handle. The flanges a³, a⁴, are similarly cut away toward their upper right hand portions, and are bent inward and lie against each other as shown in Figure 7 to form the engaging finger a⁶. t is a triangular shaped piece of sheet metal forming the trigger-piece t pivoted upon a pin ta passing through holes ta² in the flanges a³, a⁴.

The barrel and handle, or stock, are assembled as follows:

The flanges a³, a⁴, with the trigger-piece t pivoted therebetween, are inserted between the flanges b⁶, b⁷, of the barrel b. The last named flanges passing through the slots k, k, and outside of the flanges a³, a⁴ and inside of the adjacent portion of the handle a at the upper right hand portion of said handle. A pin ab is then passed through suitable apertures in the flanges b⁶, b⁷ and through the aperture ab² (Fig. 7) in the flanges a³, a⁴.

a⁷ (Fig. 7) indicates holes through the metal of the handle a where it passes over the flanges b⁶, b⁷. Suitable lugs (not shown) are formed in said flanges so that when the handle is turned to operative position said lugs shall engage in said hole to hold the handle in position.

When the handle is in the position just described the finger a^6 engages the part e^3 of the retracting wire e , as shown in Figure 2.

To "load" the pistol the handle a is 5 "broken" down as shown in Figure 3. The finger a^6 acting to carry the part e^3 of the retracting rod into position to engage the lugs b^4 formed by cutting away the rear of the barrel b . This movement of the handle 10 carries the trigger t in between the flanges b^6 and b^7 , as shown in Figure 3, where it can not be acted upon to displace the end e^3 of the retracting rod e . In this 15 motion of the handle there is no position in which the operator's hand may be engaged between the handle and trigger and until the handle is returned to its normal position the part t^2 of the trigger is so far separated from the end e^3 of the retracting rod 20 e that it cannot engage it to displace the same and the part t^2 of the trigger piece, which is engaged to "fire" the pistol is between the flanges b^6 and b^7 .

When the handle is returned to its normal 25 position the parts are in "firing" position as shown in Figure 4. The operator presses upon the edge t^2 of the trigger t to displace the end e^3 of the retracting rod e from engagement with the shoulders b^4 , the spring 30 s throws the piston d forward compressing the air before it and displacing the cork c .

When the pistol is "reloaded", as above described, the retracting of the rod e carries with it the wire f which by means of the 35 loop f^3 replaces the cork c in the end of the barrel b .

The handle and barrel may be made entirely of sheet metal and are stamped out in the form shown and described. The handle 40 at its upper right hand portion extends outside of the flanges b^6 , b^7 , relative to which the handle moves, so that the hand of the operator, grasping the handle, is held out of contact with the relatively moving parts.

45 In the modification shown in Figure 10 only one side of the handle a is slit and bent to form a flange a^3 , as above described, and there is only one flange b^6 turned down from the edge of the slot b^3 .

50 What I claim is:

1. In an apparatus of the kind described, a barrel and a handle forming constituent parts of said apparatus said handle being secured to said barrel so as to be movable relative thereto to operate the apparatus and a trigger-piece movably secured to one of said parts and adapted to be drawn into the other of said parts by the relative movement of the same.

60 2. In an apparatus of the kind described, the combination of a barrel and operative parts therein, a handle movably secured to said barrel, a trigger-piece on said handle so located that the movement of the handle 65 shall carry said trigger-piece into a position

such that it cannot cooperate with said operative parts.

3. In an apparatus of the kind described, a barrel having parallel and adjacent flanges extending therefrom, a handle pivoted between said flanges and a trigger-piece movably secured to said handle so as to be carried between said flanges by the relative movement of said handle.

4. In an apparatus of the kind described, a barrel having parallel and adjacent flanges extending therefrom, a handle pivoted between said flanges and a trigger-piece movably secured to said handle so as to be carried between said flanges by the relative movement of said handle, operative parts in 75 said barrel, said trigger-piece being so formed and located that it shall be carried out of position to cooperate with said operative parts when the handle is moved from 80 its normal position.

5. In an apparatus of the kind described, the combination of a barrel, operative parts in said barrel, said barrel being provided with a slot through the wall thereof toward 90 the rear of said barrel, flanges extending parallel to each other from the edges of said slot, and a handle pivoted to said flanges and extending in part between said flanges, and in part outside of said flanges at the 95 outer sides thereof, the part of said handle between said flanges extending through said slot to cooperate with said operative parts.

6. In an apparatus of the kind described, the combination of a barrel, operative parts in said barrel, said barrel being provided with a slot through the wall thereof toward the rear of said barrel, flanges extending parallel to each other from the edges of said slot, and a handle pivoted to said flanges 100 and extending in part between said flanges, and in part outside of said flanges at the outer sides thereof, the part of said handle between said flanges extending through said slot to cooperate with said operative parts, 105 and a trigger-piece pivoted to said handle between said flanges.

7. In an apparatus of the kind described, the combination of a barrel, operative parts in said barrel, said barrel being provided 110 with slot toward the rear of said barrel, a flange extending from one edge of said slot, and a handle pivoted to said flange, one side of said handle extending in part along the inner surface of said flange and in part 115 along the outer surface of said flange and the other side of said handle extending parallel to the first named side, the part of the first mentioned side of said handle extending through said slot to cooperate with said 120 operative parts.

8. In an apparatus of the kind described, the combination of a barrel, operative parts in said barrel, said barrel being provided with a slot toward the rear of said barrel, a 125

flange extending from one edge of said slot, a handle pivoted to said flange, one side of said handle extending in part along the inner surface of said flange and in part along 5 the outer surface of said flange, and the other side of said handle extending parallel to the first named side, and a trigger-piece secured to the part of the first named side of said handle that extends along the inner 10 surface of said flange so as to cooperate with said operative parts.

9. In an apparatus of the kind described, the combination of a barrel having operative parts therein, said barrel being provided 15 with a slot toward the rear of said barrel, a flange extending from one edge of said slot, a handle pivoted to said flange, a wall of said handle being slotted downward from near the center of its upper edge, the wall 20 on one side of said slit being bent inward then outward parallel to the rest of said wall, the bent in portion of said wall lying inside of said flange and being adapted to cooperate with said operating parts, and 25 the part of the wall on the other side of said slit lying outside of said flange.

10. In an apparatus of the kind described, the combination of a barrel having operative parts therein and provided with a slot toward its rear end, parallel flanges extending from the edges of said slots, a handle pivoted to said flanges having its side walls slit downward from toward the centers of 30 their upper edges, the parts in front of said

slits being bent inward and then upward 35 to parallel positions, said bent in portions lying between said flanges, the part of the walls back of the bent in portions lying along the outside of said flanges and a trigger-piece pivoted between the bent in portions of said wall substantially as and for 40 the purpose described.

11. In an apparatus of the kind described, the combination of a barrel having operative parts therein including a retracting wire 45 having its rear end formed into a catch, the rear end of said barrel having an exposed edge said catch being adapted to engage over said exposed edge.

12. In an apparatus of the kind described, 50 the combination of a barrel having a longitudinal slot toward its rear end and a guide portion at its forward end, a piston adapted to reciprocate in said barrel and having a wire *e* extending rearwardly therefrom and 55 through said slot, a spring adapted to drive said piston forward, a cork adapted to travel in said guide, and to be inserted in said barrel in front of said cork, a wire engaging the part of the wire *e* that extends through 60 said slot and adapted at its other end to travel in said guide and to engage said cork to insert the same in the barrel, and means for retracting the wire *e* and said piston and releasing the same.

In testimony whereof, I sign this specification.

WILLIAM F. SCHMIDT.
